US0D1083866S

(12) **United States Design Patent** (10) **Patent No.:** **US D1,083,866 S**
(45) **Date of Patent:** **** Jul. 15, 2025**

(54) **FIBER OPTIC SPLICE CLOSURE**

(71) Applicant: **Yaoz Solutions Ltd.**, Nes Ziona (IL)

(72) Inventor: **Zachi Gal**, Givatayim (IL)

(73) Assignee: **Yaoz Solutions Ltd.**, Nes Ziona (IL)

(**) Term: **15 Years**

(21) Appl. No.: **35/517,010**

(22) Filed: **Feb. 8, 2023**

(80) **Hague Agreement Data**

Int. Filing Date: **Feb. 8, 2023**

Int. Reg. No.: **DM/228364**

Int. Reg. Date: **Feb. 8, 2023**

Int. Reg. Pub. Date: **Apr. 28, 2023**

(30) **Foreign Application Priority Data**

Aug. 11, 2022 (IL) 69188

(51) **LOC (15) Cl.** **14-03**

(52) **U.S. Cl.**

USPC **D14/140.6**; D13/184; D14/240

(58) **Field of Classification Search**

USPC D13/184; D14/242, 299, 300, 356, 357,
D14/240, 140.2, 140.5, 140.6

CPC G02B 6/444; G02B 6/4441; G02B 6/4455

See application file for complete search history.

(57) **CLAIM**

The ornamental design for a fiber optic splice closure as shown and described.

DESCRIPTION

3. Fiber optic splice closure

3.1: front top perspective view

3.2: Back

3.3: Front

3.4: Left

3.5: Right

3.6: Top

3.7: Bottom

3.8: back bottom perspective view

3.9: exploded back bottom perspective view

(Continued)

Broken lines seen in the reproductions depict portions of the fiber optic splice closure which form no part of the claimed design.

1 Claim, 9 Drawing Sheets
